UNITED STATES PATENT OFFICE.

WALLACE LANGDON NEWELL, OF BUCKEYE, WASHINGTON.

SWAGE FOR INSERTED SAW-TEETH.

No. 836,527.

Specification of Letters Patent.

Patented Nov. 20, 1906.

Application filed June 10, 1905. Serial No. 264,609.

To all whom it may concern:

Be it known that I, WALLACE LANGDON NEWELL, a citizen of the United States, and a resident of Buckeye, in the county of 5 Spokane and State of Washington, have invented a new and Improved Swage for Inserted Saw-Teeth, of which the following is a full, clear, and exact description.

This invention relates to machines for 10 swaging saw-teeth, and is especially useful for swaging such teeth when removed from the body of the saw.

The object of the invention is to provide 15 improved means for holding the teeth against the anvil and swage during the swaging operation.

The invention constitutes an improvement on the invention described in application made by Ulysses Staley and myself, filed 20 June 3, 1904, Serial No. 210,967.

The invention consists in the construction and combination of parts to be more fully described hereinafter, and definitely set forth in the claims.

Reference is to be had to the accompanying drawings, forming a part of this specification, in which similar characters of reference indicate corresponding parts in all the figures.

30 Figure 1 is a side elevation of the machine, certain parts being broken away, this view showing the machine in an open position in which the tooth may be inserted preparatory to swaging its point. Fig. 2 is a vertical section taken upon the line 2 2 of Fig. 1. Fig. 3 is substantially a vertical section taken upon the line 3 3 of Fig. 4, a portion of the body of the machine being shown in elevation and the operating-lever represented as broken 35 away. Fig. 4 is a plan, the operating-lever being represented as broken away, as in Fig.

3. Fig. 5 is a horizontal cross-section taken upon the line 5 5 of Fig. 3 and illustrating the manner of securing the tooth in the machine. 40 Fig. 6 is a detail showing a portion of a tooth being operated upon between the anvil and the swage, the swage being represented in cross-section. Fig. 7 is a side elevation of the clip or templet which constitutes a part 45 of my invention. Fig. 8 is a perspective of the tooth-holder. Fig. 9 is a perspective showing a portion of the swage and showing how the swaging-face is applied to the tooth preparatory to swaging the tooth; and Fig.

50 55 10 is a view similar to Fig. 9 and representing

the swage after the movement which it takes in the swaging operation. The tooth in this view is represented as spread or swaged at its point.

Referring more particularly to the parts, 1 60 represents the frame or body of the machine, which consists of a massive pillow-block, preferably of cast-iron and formed with a suitable base 2, adapted to be bolted securely to the floor. On the forward face of this 65 pillow-block a vertically-disposed channel 3 is provided, and passing transversely through this channel a horizontal shaft 4 is rotatably mounted. This shaft, as indicated most clearly in Fig. 2, is provided at its middle 70 portion with a recess 5, presenting a depressed face 6. This shaft 4 constitutes a swage. It is preferably provided with a squared extremity 7, to which a suitable operating-lever 8 is attached by a nut 9, as indicated. 75 Its opposite extremity is formed with circumferential grooves 10 10^a, in either of which there is received a clip or templet 11. The construction of this templet is very clearly shown in Figs. 2 and 7. It is 80 formed with a semicircular notch 12 in its upper edge, which is received in one of the grooves 10 or 10^a to hold the swage in position. The body of the templet 11 is formed with a vertically-disposed slot 13, through 85 which passes a removable bolt 14, enabling the templet or clip to be adjusted toward the body of the swage, as desired. This clip, when applied as indicated in Fig. 2, affords means for limiting the longitudinal movement of 90 the swage. It has other functions which will be described more fully hereinafter.

In the channel 3 above the swage I provide an anvil 15, which consists of a block of hard metal having a beveled swage-face 16 and a 95 rear beveled face 17. As indicated most clearly in Fig. 3, the channel 3 does not extend completely to the upper face of the pillow-block; but the material of the pillow-block overhangs the channel, as shown. 100 Through the upper face of the pillow-block an adjusting-screw 18 passes, the tip whereof engages the upper face of the anvil 15, as indicated. The side of the anvil rests against the bottom vertical face 19 of the channel 3. 105 In the side of the anvil a shallow vertical groove 20 is formed, and in the side of the pillow-block a set-screw 21 is mounted which projects into the channel 3, as indicated, the extremity of this set-screw resting in the 110

groove 20 in order to enable the anvil to be clamped in any position desired, as will be readily understood.

Near the lower and forward portion of the 5 pillow-block 1 it is formed with webs 22, located at the side, and between these webs a tooth-carrier 23 is rotatably mounted upon a horizontal transverse pivot-bolt 24. The 10 construction of this tooth-carrier is very 10 clearly shown in Figs. 1 and 5. It consists of a short flat arm, presenting a recess 25 on its cheek, the said recess being preferably of rectangular form, as shown. In this recess 25 a tooth-holder 26 is attached by means of bolts 15 27, which pass through vertically-elongated slots 28, as indicated. This tooth-holder is clearly illustrated in Fig. 8. Upon its inner 20 face there is formed a pocket 29, which is adapted to receive the shank of a tooth 30, 25 which is to be swaged. The form of this pocket and the manner in which the tooth is held therein will be described more fully hereinafter. At its outer extremity the tooth-carrier 23 is provided with an offset 30 ear 31, and to its end a clamp-link 32 is attached pivotally by means of a suitable bolt 33. This link 32 is formed with separated side arms 34, which arms near the ear 31 are connected by a transverse bar 35. Through 35 the head 36 of this link a clamping-screw 37 passes, the same being provided, preferably, with a check-nut 38, as shown.

As indicated most clearly in Fig. 3, the upper wall of the pillow-block is extended forwardly and on its under side is formed with an arcuate lip 39, and the upper or outer extremity of the tooth-carrier 23 is likewise formed with a lip 40, which is adapted to be received under the lip 39, as indicated in Fig. 3. It may be said at this point that the purpose of this arrangement is to hold the tooth-carrier very securely when the tooth is being applied to the swage. The link 32 affords means for holding the tooth-carrier in the position shown in Fig. 3. For this purpose the rear side of the pillow-block 1 is formed with an upwardly-projecting lug 41, which extends above the upper wall of the pillow-block, as shown. In order to clamp the tooth-carrier in the position shown, the link will be rotated upon its pivot-bolt 33, so as to dispose the same substantially horizontal above the upper face of the pillow-block. In this way the lug 41 will pass into the space 55 between the arms 34 and will lie adjacent to the head 36 of the link. The clamping-screw 37 will then be tightened up, so as to force the tooth against the anvil. As indicated most clearly in Figs. 3 and 4, the ear 31 60 is provided with a lug 42, which presents a radial face or shoulder 43, and this shoulder lies in the path of the bar 35 in rotating upon the pivot-bolt 33. After the swaging operation the link 32 is freed by loosening the 65 clamping-bolt 37 and is then rotated up-

wardly until the bar 35 engages the shoulder 43. The link then operates as a lever, enabling the tooth-carrier to be forced out of its intimate contact with the pillow-block.

It should be understood that the form of the pocket 29 of the tooth-holder corresponds to the particular standard or form of tooth being swaged. Such teeth generally have substantially the form of the tooth 30. (Shown in Fig. 3, presenting a curved shank 44.) In order to receive such a tooth, the pocket 29 should have the form indicated, presenting a curved rear face 45, adapted to receive the rear side of the shank, as shown in Fig. 3. At the inner extremity the pocket presents an inclined face 46, against which the extremity of the shank is adapted to abut, as indicated in Fig. 3. Beyond this inclined face 46 the forward portion of the pocket is cut away, as indicated at 47, so as to present an enlarged opening through which the tooth may be readily inserted. With this form of pocket the pressure upon the point of the tooth which tends to force the same rearwardly is resisted by the curved face 45 and by the inclined face 46. As indicated, the rear of the head of the tooth is formed with a small shoulder 48, Fig. 6, which is adapted to abut against an inclined forwardly-projecting shoulder 49, which is formed on the forward edge of the tooth-carrier, as indicated most clearly in Fig. 1.

The teeth to be swaged are inserted one by one in the pocket 29 of the tooth-holder. The tooth-holder used would correspond to the form of these teeth and would have one of another form substituted for swaging teeth of another form. The slots 28 enable the tooth-holder to be adjusted vertically.

In operation the tooth-carrier would be held upwardly, as indicated in Fig. 1, and the link 32 locked over the lug 41 in the manner described above. The point of the tooth 30 would then lie adjacent to the swaging-face 6, the outer face of the tooth coming against the beveled face 16 of the anvil. In order to swage the tooth, the operating-lever 8 would be rotated in the direction indicated by the arrows in Figs. 1 and 3. As the swage is rotated the swaging-face 6 operates to pinch the point of the tooth against the beveled face 16, as indicated most clearly in Fig. 6. In Fig. 9 the unswaged tooth is represented as applied to the swage, and in Fig. 10 the tooth is represented after being swaged, and the swage is represented in substantially the position to which it must be rotated in order to swage the tooth as indicated.

Referring again to the clip 11 or templet and especially to Fig. 7, the lower portion of this clip is cut away so as to form a notch 51. This notch has a vertical edge 52 and an inclined edge 53. The inclination of the edge 53 corresponds to that of the beveled face 16 of the anvil 15. This notch 51 constitutes a 130

templet to facilitate the grinding of the anvil, and for this purpose it is provided with a mark 54. In using the templet for gaging an anvil which is being ground the anvil is applied from time to time to the notch 51, as indicated by dotted lines in Fig. 7, and the rear face of the block indicated by the line 55 is ground away more or less, as desired. Where a normal point for the tooth were desired, the grinding is discontinued when the two beveled faces of the anvil meet at the mark 54, but if a more obtuse point were desired the grinding upon the rear face 17 would be continued until the point of the anvil was advanced farther toward the vertex of the notch. In this way the clip 11 operates as a templet for gaging the grinding of the anvil.

In order to facilitate the removing of the anvil I provide an opening 56, which extends through the rear face of the pillow-block to the bottom of the channel, and through this opening a suitable instrument may be inserted, so as to force the anvil out of the channel, it being understood that the screws for clamping the anvil would be previously disengaged therefrom.

Special attention is called to the arrangement for holding the saw-tooth in the holder. With the arrangement described an enlarged opening is presented through which the saw-tooth may be inserted without the least difficulty, and after being inserted the tooth will be very firmly held without the use of springs, clamping-bolts, or other devices.

Having thus described my invention, I claim as new and desire to secure by Letters Patent—

1. In a machine of the class described, in combination, a pillow-block having a channel therein, a swage disposed transversely of said channel, an anvil disposed near said swage, a tooth-carrier pivoted to said pillow-block, a link pivoted to said tooth-carrier and adapted to clamp to said pillow-block, said pillow-block having an overhanging wall presenting an inclined lip and said tooth-carrier having a beveled lip coöperating with said first lip.

2. In a machine of the class described, in combination, a pillow-block, a swage and an anvil mounted therein, a tooth-carrier pivoted to said pillow-block, a link pivoted to said tooth-carrier and adapted to clamp to said pillow-block, said pillow-block having beveled lips adapted to engage, and means for limiting the pivotal movement of said link upon said tooth-car-

rier whereby said link may operate as a lever to disengage said tooth-carrier.

3. In a machine of the class described, in combination, a pillow-block, a swage and an anvil mounted therein, a tooth-carrier pivoted to said pillow-block, said pillow-block and said tooth-carrier having beveled lips adapted to be jammed together, a link attached to said tooth-carrier and adapted to clamp said pillow-block, said tooth-carrier having a projection, said projection lying in the path of a part of said link and affording means for limiting the pivotal movement of said link upon said tooth-carrier whereby said link may operate as a lever to disengage said tooth-carrier.

4. In a machine of the class described, in combination, a pillow-block having a channel formed therein, a swage rotatably mounted in said channel, an anvil disposed adjacent to said swage and also mounted in said channel, a tooth-carrier pivoted to said pillow-block and having an inclined lip near the outer extremity thereof, said pillow-block having an overhanging wall presenting an inclined lip receiving said first lip, a link pivotally attached to said tooth-carrier and having substantially parallel arms with a transverse bar therebetween, said tooth-carrier having a projection lying in the path of said bar, a clamping-bolt carried by the extremity of said link, said pillow-block having a lug adapted to receive said clamping-bolt.

5. In a machine of the class described, a tooth-holder adapted to receive a tooth to be swaged, said tooth-holder presenting a pocket for said tooth, said pocket having a curved face adapted to receive the curved wall of the shank of the tooth and an inclined wall adapted to receive the extremity of said shank, said pocket affording sole means by its form for holding the tooth.

6. In a machine of the class described, in combination, a pillow-block, an anvil and a swage carried therein, a tooth-carrier pivotally mounted on said pillow-block, a link attached to said tooth-carrier and having a cross-head adapted to engage said pillow-block to lock said tooth-carrier thereagainst.

In testimony whereof I have signed my name to this specification in the presence of two subscribing witnesses.

WALLACE LANGDON NEWELL.
